CLAIM

The ornamental design for a vehicle seat, as shown and described.

DESCRIPTION

FIG. 1 is a right, front perspective view of a vehicle seat according to a first embodiment of the present invention, wherein a left, front perspective view of the vehicle seat shown in FIG. 1 is a mirror image of FIG. 1;

FIG. 2 is a left elevation view of the vehicle seat shown in FIG. 1, wherein a right elevation view of the vehicle seat shown in FIG. 1 is a mirror image of FIG. 2;

FIG. 3 is a front elevation view of the vehicle seat shown in FIG. 1;

FIG. 4 is a rear elevation view of the vehicle seat shown in FIG. 1;

FIG. 5 is a top plan view of the vehicle seat shown in FIG. 1;

FIG. 6 is left, rear perspective view of the vehicle seat shown in FIG. 1, wherein a right, rear perspective view of the vehicle seat shown in FIG. 1 is a mirror image of FIG. 6;

FIG. 7 is a right, front perspective view of a vehicle seat according to a second embodiment of the present invention, wherein a left, front perspective view of the vehicle seat shown in FIG. 7 is a mirror image of FIG. 7;

FIG. 8 is a left elevation view of the vehicle seat shown in FIG. 7, wherein a right elevation view of the vehicle seat shown in FIG. 7 is a mirror image of FIG. 8;

FIG. 9 is a front elevation view of the vehicle seat shown in FIG. 7;

FIG. 10 is a rear elevation view of the vehicle seat shown in FIG. 7;

FIG. 11 is a top plan view of the vehicle seat shown in FIG. 7;

FIG. 12 is left, rear perspective view of the vehicle seat shown in FIG. 7, wherein a right, rear perspective view of the vehicle seat shown in FIG. 7 is a mirror image of FIG. 12;

FIG. 13 is a right, front perspective view of a vehicle seat according to a third embodiment of the present invention, wherein a left, front perspective view of the vehicle seat shown in FIG. 13 is a mirror image of FIG. 13;

FIG. 14 is a left elevation view of the vehicle seat shown in FIG. 13, wherein a right elevation view of the vehicle seat shown in FIG. 13 is a mirror image of FIG. 14;

FIG. 15 is a front elevation view of the vehicle seat shown in FIG. 13;

FIG. 16 is a rear elevation view of the vehicle seat shown in FIG. 13;

FIG. 17 is a top plan view of the vehicle seat shown in FIG. 13;

FIG. 18 is left, rear perspective view of the vehicle seat shown in FIG. 13, wherein a right, rear perspective view of the vehicle seat shown in FIG. 13 is a mirror image of FIG. 18;

FIG. 19 is a right, front perspective view of a vehicle seat according to a fourth embodiment of the present invention, wherein a left, front perspective view of the vehicle seat shown in FIG. 19 is a mirror image of FIG. 19;

FIG. 20 is a left elevation view of the vehicle seat shown in FIG. 19, wherein a right elevation view of the vehicle seat shown in FIG. 19 is a mirror image of FIG. 20;

FIG. 21 is a front elevation view of the vehicle seat shown in FIG. 19;

FIG. 22 is a rear elevation view of the vehicle seat shown in FIG. 19;

FIG. 23 is a top plan view of the vehicle seat shown in FIG. 19;

FIG. 24 is left, rear perspective view of the vehicle seat shown in FIG. 19, wherein a right, rear perspective view of the vehicle seat shown in FIG. 19 is a mirror image of FIG. 24;

FIG. 25 is a right, front perspective view of a vehicle seat according to a fifth embodiment of the present invention, wherein a left, front perspective view of the vehicle seat shown in FIG. 25 is a mirror image of FIG. 25;

FIG. 26 is a left elevation view of the vehicle seat shown in FIG. 25, wherein a right elevation view of the vehicle seat shown in FIG. 25 is a mirror image of FIG. 26;

FIG. 27 is a front elevation view of the vehicle seat shown in FIG. 25;

FIG. 28 is a rear elevation view of the vehicle seat shown in FIG. 25;

FIG. 29 is a top plan view of the vehicle seat shown in FIG. 25; and,

FIG. 30 is left, rear perspective view of the vehicle seat shown in FIG. 25, wherein a right, rear perspective view of the vehicle seat shown in FIG. 25 is a mirror image of FIG. 30.

The broken lines shown herein are for illustrative purposes and form no part of the claimed design. For example, the broken lines in the backrest of the first embodiment are boundaries, and the areas within these boundaries (i.e., the boundaries defined by the broken lines in the backrest of the first embodiment) are not part of the claimed design.
